Frank K. Reid
INVENTOR
BY Victor J. Evans

WITNESS:

ATTORNEY

UNITED STATES PATENT OFFICE.

FRANK K. REID, OF ALVA, OKLAHOMA.

LIGHT DEFLECTOR.

Application filed February 19, 1925. Serial No. 10,355.

To all whom it may concern:

Be it known that I, FRANK K. REID, a citizen of the United States, residing at Alva, in the county of Woods and State of

Oklahoma, have invented new and useful Improvements in Light Deflectors, of which the following is a specification.

This invention is a light reflector for rooms and its principal object is to provide a light reflector which will diffuse and reflect the sun to the ceiling of a roof of a building instead of permitting the sun to shine directly upon the floor.

A further object of the invention is to provide a reflector which can be adjusted to reflect the desired amount of light as well as to concentrate the light at any particular spot upon the ceiling.

Still another object of the invention is to provide a light reflector of this character which will not interfere with the opening or closing of the window to control the ventilation into the latter.

With the preceding and other objects and advantages in view, the invention consists in the novel combination of elements, arrangements of parts and operations, to be specifically referred to, and illustrated in the accompanying drawings, wherein:

Figure 1 is a vertical sectional view of a room and window embodying my improved light reflector.

Figure 2 is a longitudinal sectional view of the reflecting and diffusing glass.

Figure 3 is a detail sectional view taken on line 3—3 of Figure 1.

Referring to the drawings in detail wherein corresponding characters of reference denote corresponding parts throughout the several views, the numeral 5 designates a school, office room or the like equipped with vertical movable windows 6 with the usual shade curtains 7. This curtain 7 is mounted at the upper end of the lower sash and is adapted to normally overlie this lower sash.

A rectangular frame 10 is hinged to the window frame at a point slightly above the shade curtain mounting as indicated at 11 and supported within this frame is a mirror 12 having an irregular inner surface 13 the purpose of which is to diffuse the light rays reflected thereon from the sun as shown.

The frame 10 also includes spacing elements 14 which are arranged upon the under face of the reflecting mirror and supported with- 55 in the frame 10.

A channel shaped casing 15 is mounted upon the window frame at one side thereof and is provided with laterally extending ears 16 for securing the same to the window 60 frame. This casing is provided with a vertical slot 17 and a series of corrugations or seats 18 that are spaced as shown. A link 19 is pivoted to one end of the frame 10 as illustrated and has its opposite end extended 65 through the slot 17 and is vertically adjustable therein. A transverse pin 20 is carried by the inner end of the link 19 and is adapted to be accommodated in any one of the seats or corrugations 18 for the purpose 70 of holding the frame and mirror 13 at any desired angle to concentrate the light rays as desired.

In the operation of the invention the light rays from the sun will shine upon the irregular surface 13 as indicated in broken lines and thence be reflected upwardly onto the ceiling of the room and then downwardly into the room. The irregular surface serves to fulcrum or diffuse the light rays 80 and hence prevent glare.

While I have shown and described the preferred embodiment of the invention, I desire to have it understood that such changes may be made in the form, construction and 85 arrangement of parts and operations as will not depart from the spirit of the invention or the scope of the subjoined claim.

What is claimed is:

The combination with a structure having 90 a window, of a reflecting glass arranged at one side of the window and capable of being arranged at any desired angle to reflect sun rays onto the ceiling of a room, means for supporting the reflecting mirror at various 95 angles, such means including a vertically arranged casing having a longitudinal slot and a series of transverse seats, a link connected with the mirror and having one end passed into the slot and a pin carried by the link 100 and engageable with any one of the seats.

In testimony whereof I affix my signature.

FRANK K. REID.
